US0D1028951S

(12) **United States Design Patent** (10) **Patent No.:** **US D1,028,951 S**
(45) **Date of Patent:** **** May 28, 2024**

(54) **ANTENNA**

- (71) Applicant: **Mitsubishi Electric Corporation**,
Tokyo (JP)
- (72) Inventors: **Kei Yokokawa**, Tokyo (JP); **Narihiro Nakamoto**, Tokyo (JP); **Toru Fukasawa**, Tokyo (JP); **Hitoshi Arai**, Tokyo (JP); **Tomohiro Takahashi**, Tokyo (JP); **Kensuke Iwaki**, Tokyo (JP); **Takamichi Kono**, Tokyo (JP); **Keisuke Fujiwara**, Tokyo (JP); **Kenjiro Takanishi**, Tokyo (JP); **Tatsuya Sakamoto**, Tokyo (JP); **Naoya Noguchi**, Tokyo (JP)
- (73) Assignee: **Mitsubishi Electric Corporation**,
Tokyo (JP)
- (**) Term: **15 Years**
- (21) Appl. No.: **29/822,520**
- (22) Filed: **Jan. 10, 2022**

(57) **CLAIM**

The ornamental design for an antenna, as shown and described.

DESCRIPTION

FIG. 1 is a perspective view of an antenna showing our new design;

FIG. 2 is a front view thereof;

FIG. 3 is a rear view thereof;

FIG. 4 is a top plan view thereof; a bottom view being a minor image;

FIG. 5 is a right side view thereof; a left side view being a minor image;

FIG. 6 is an enlarged view of 6-6 part shown in FIG. 2 thereof;

FIG. 7 is an enlarged view of 7-7 part shown in FIG. 3 thereof;

FIG. 8 is an end view of cutting part at 8-8 of FIG. 6 thereof; and,

FIG. 9 is an enlarged view of 9-9 part shown in FIG. 8 thereof.

The broken lines shown represent portions of the antenna and form no part of the claimed design.

The dot-dash broken lines illustrate a boundary of the claimed design and form no part of the claimed design.

1 Claim, 9 Drawing Sheets
